(57) **CLAIM**

The ornamental design for a head mountable display visor, as shown and described.

DESCRIPTION

FIG. 1 is a perspective view of a head mountable display visor according to my design;

FIG. 2 is a front view thereof;

FIG. 3 is a back view of the head mountable display visor of FIG. 1, wherein the back retaining strap is removed;

FIG. 4 is a top view of the head mountable display visor of FIG. 1, wherein the top retaining strap is removed;

FIG. 5 is a bottom view thereof;

FIG. 6 is a right side view of the head mountable display visor of FIG. 1; and,

FIG. 7 is a left side view thereof.

The broken lines in the drawings illustrate unclaimed portions of the head mountable display visor and form no part of the claimed design.
